(57) **CLAIM**

The ornamental design for a combined wash basin and stand, as shown and described.

DESCRIPTION

FIG. 1 is a front and top perspective view of a combined wash basin and stand, showing my new design;

FIG. 2 is a rear and bottom perspective view thereof;

FIG. 3 is an exploded view of the combined wash basin and stand of FIG. 1, showing the wash basin being lifted from the stand;

FIG. 4 is a front and top perspective view of the wash basin part of the article;

FIG. 5 is a rear and bottom perspective view thereof;

FIG. 6 is a front elevation view thereof, the rear elevation view, left side elevation view and right side elevation view being the same as the front elevation view;

FIG. 7 is a top plan view thereof;

FIG. 8 is a bottom plan view thereof;

FIG. 9 is a front and top perspective view of the stand part of the article;

FIG. 10 is a rear and bottom perspective view thereof;

FIG. 11 is a front elevation view thereof;

FIG. 12 is a rear elevation view thereof;

FIG. 13 is a left side elevation view thereof, the right side elevation view being a mirror image;

FIG. 14 is a top plan view thereof; and,

FIG. 15 is a bottom plan view thereof.

The broken lines in the figures depict portions of the combined wash and basin stand that form no part of the claimed design.

The wash basin part and the stand part of the combined wash basin and stand are shown separately in the drawings for clarity.
